AIR-SUPPLYING MEANS FOR STOKERS

Edgar L. Zehrbach, Findlay, Ohio

Application July 15, 1936, Serial No. 98,778

3 Claims. (CL. 110—45)

This invention aims to provide a novel means whereby, without drilling, and by a simple punching or knock-out process, an additional air supply may be afforded through the tuyères and the dead plates of a mechanical stoker.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in vertical section, a portion of a stoker equipped with the device forming the subject matter of this application;

Fig. 2 is a side elevation showing one of the tuyère members;

Fig. 3 is an elevation showing the inner side of the tuyère member;

Fig. 4 is an elevation showing the outer side of the tuyère member;

Fig. 5 is a top plan of the tuyère member; and

Fig. 6 is a horizontal section of the structure delineated in Fig. 1, most parts appearing in top plan.

The numeral 1 marks a casing, which may be of any desired size and shape, the casing constituting part of a mechanical stoker. The casing 1 is the combustion chamber lining, usually made of fire brick for insulating and more complete combustion purposes. Dead plates 3 are supported on the casing 1. Fuel is fed through a conduit 4, by a conveyor 5. The conduit 4 has an upwardly extended mouth 6 which constitutes the base of a retort. At its upper end, the base portion 6 of the retort has an outstanding rim 7. A chamber 8 exists in the casing 1, about the base 6 of the retort, and into this chamber, air is forced under pressure, by any suitable means, not shown in the drawings, and constituting no part of the present invention.

The upper member of the retort is marked by the numeral 9, and is composed of a plurality of tuyères 10, located side by side. Each tuyère 10 comprises an outer wall 11, at the upper end of which there is a head 12, connected to a depending inner wall 14, the inner wall 14 being

joined, intermediate its side edges, to the outer wall 11, by a vertical web 15, extended upwardly to the head 12. The web 15 forms vertical air channels 20 on each side of the web 15 of each tuyère, and, therefore, between the webs of adjoining tuyères. At the lower end of the inner wall 14 of the tuyère there is a jaw 17 which receives the rim 7 of the base 6 of the retort.

At the lower end of the outer wall 11 of each tuyère there is an outstanding lug 18, which is engaged beneath the dead plates 3. Along one side of the web 15, a rib 16 extends between the outer wall 11 of the tuyère and the inner wall 14 thereof. On the opposite side of the web 15, a projection 19 is formed integrally with the outer wall 11 and extends between the web 15 and one edge of the wall 11, as shown in Fig. 3.

Ducts 21, of L-shape, are formed in opposite sides of the head 12. The ducts 21 comprise, each, a horizontal portion 22, opening into the upper member 9 of the retort, and a vertical depending portion 23, communicating with the corresponding air channel 20. In the outer surface of the head 12 (Fig. 4), oppositely disposed notches 24 are formed, and these notches are separated from the horizontal portions 22 of the ducts 21 by thin breakable fins 25. Oppositely disposed openings 26 are formed in opposite edges of the inner wall 14, as shown in Fig. 3 and establish communication between the interior of the upper member 9 of the retort and the air channels 20. The openings 26 are closed to any desired extent by thin, breakage fins 27, formed integrally with the inner wall 14.

Slots 28 are formed in the dead plates 3 and 35 are bridged across by thin partitions 29.

Fuel is conveyed from a source of fuel supply, through the conduit 4, by the appliance shown at 5, or by an equivalent means. The fuel is forced upwardly through the retort 6—8. Air is forced through the chamber 8, and through the air channels 20, the air entering the retort by way of L-shaped ducts 21 in the tuyères. Air also enters the retort through the openings 26, if the fins 27 are not large enough to close the openings 26 completely. The size and shape of the air openings in the tuyères 10 are so designed as to meet firing conditions encountered with the average grade of coal. However, in some cases, where a slowly burning coal is supplied to the stoker, the amount of air passing through the tuyères 10, as above described, is insufficient to consume the fuel entirely, and some of the fuel is deposited on the dead plates 3, in the form of residual coke. In order to consume 55

the residual coke completely, under the conditions mentioned, it is necessary to have an additional air supply through the tuyères 10, and sometimes through the dead plates 3. This is accomplished by knocking out with a hammer and punch, as many of the thin, breakable fins 25 and 27 as may be required, it being possible, also, to knock holes 30 through the thin partitions 29 in the slots 28 of the dead plates 3.

It is not practical to drill holes, like the holes 30, in the dead plates 3, since this is a tiresome job, owing to the thickness of the dead plates. The tuyères 10 cannot be drilled as above described, because, generally stated, they are inaccessible to a boring tool. When, however, the present invention is put into practice, all that the operator has to do is to knock out with a punch and hammer, so much of the partitions 29, and so many of the fins 25 and 27, as may be found expedient.

Having thus described the invention, what is claimed is:

1. In a device of the class described, a tuyère comprising an outer wall, an inner wall, a head joining the walls, and a web connected to the walls and to the head and forming air channels on opposite sides of the web, the head being provided with ducts leading from the air channels to the inner surface of the tuyère, the head being provided on its outer side with openings, and the head being supplied with thin breakable fins having edge connection with the head and interposed

between the openings and the ducts, the fins controlling the passage of air, prior to breaking, and affording air passages of increased size, after breaking.

2. In a device of the class described, a tuyère comprising an outer wall, an inner wall, a head joining the walls, and a web connected to the walls and to the head and forming air channels on opposite sides of the web, the inner wall being provided with openings leading from the air channels to the inner surface of the tuyère, the tuyère being supplied with thin breakable fins, having edge connection with the tuyère, the fins being located in the openings, the fins controlling the passage of air, prior to breaking, and affording air passages of increased size, after breaking.

3. In a device of the class described, a retort comprising a tuyère having an opening for the passage of air, the tuyère being provided with an integral fin having edge connection with the tuyère and located in the opening and much thinner than the material through which the opening extends, the opening forming a punch-guide, and the fin being so thin, within the contour of the opening, as to be there breakable by a punching operation, the fin, prior to breaking, controlling the passage of air through the opening and affording an air passage of increased size, after breaking.
